UNITED STATES PATENT OFFICE

LOUIS J. VETTER, OF ATTLEBORO, MASSACHUSETTS, ASSIGNOR TO BLISS BROTHERS CO.,
OF ATTLEBORO, MASSACHUSETTS

BRACELET CLASP

Application filed April 11, 1931. Serial No. 529,372.

This invention relates to bracelet clasps and the primary object thereof is to provide a clasp structure wherein the parts are secured in position without the use of solder or screws 5 or similar fastenings.

More particularly the invention relates to clasps which are used in connection with bracelets of the extensible type so as to enable the bracelet, upon extension, to be placed over 10 the hand of the wearer.

The invention further aims to provide a bracelet clasp which is of simple construction and which can be easily and quickly assembled.

15 The invention has further and other objects which will be later set forth and manifested in the course of the following description.

In the drawings:—

20 Figure 1 is a top plan view of a bracelet showing the parts in connected position;

Figure 2 is a top edge plan view of Figure 1;

25 Figure 3 is an inside elevation of Figure 1; Figure 4 is an elevation of the parts in extended position;

Figure 5 is a similar view of the reverse side;

Figure 6 is a section on line 6—6 of Figure 30 1; and

Figure 7 is a section on line 7—7 of Figure 5.

In proceeding in accordance with the present invention a pair of members 1 and 2 which 35 are curved to conform to the wrist are employed, and of which 1 is a front member, and the rear member is 2. One end 3 of the bracelet is secured at 4 to the rear member 2 while the other end 5 of the bracelet is secured at

40 6 to the front member 1. The members 1 and 2 are pivotally or hingedly connected by a pin 7 and as shown in Figure 2 are adapted to overlie one another. As shown particularly in Figure 7 the front member

45 1 has its side edges off-set as indicated at 8 to form right angular walls 9 which latter are slotted at 10 and also at 11. A substantially U-shaped catch member 12 which is formed of an integral stamping

50 and of resilient or spring metal is employed,

the closed end of which catch is formed with outwardly projecting lugs 13 that are received in the slots 11, whereby the base end of the catch is secured in position. Outwardly projecting finger engaging lugs or parts 14 55 are provided near the open end of the catch and extend freely through the slots 10 whereby upon engaging the fingers with each of the finger parts 14 the free ends of the catch can be moved toward one another as is obvious 60 from inspection of Figure 5.

As shown particularly in Figures 4 and 5 of the drawings the rear member 2 is formed with a pair of spaced opposed struck out keepers 15 which latter are receivable in cut 65 outs 16 provided therefor in the member 1. The free end portions of the catch further has U-shape cut-outs 17 which receive the keepers 15, the latter being of substantially L-shape so that when the same snaps pass the 70 free end of the catch the parts will be held in latched position.

Referring to Figure 5 of the drawings, it will be noted that the back member 2 is formed with side flanges 18 between which 75 the central portion of the back of the member 1 is received when the parts are in folded position and same further has off set portions 19 to receive the finger engaging parts 14 of the catch when the parts occupy the 80 folded position shown in Figure 2 of the drawings.

In assembly the finger engaging parts are projected through the slots 10. The closed end of the U-catch is then bent or curved 85 longitudinally so as to bring the end lugs 13 closer together whereupon the ends are aligned with the slots 11 and the end of the catch then rebent to its original position which causes the lugs 13 to project through 90 the slots 11.

The connecting member 6 of the end 5 of the bracelet as shown in Figure 5 of the drawings overlies the free ends of the U-catch and serves to house and protect same. 95

From the foregoing and as shown in Figure 2 of the drawings it will be seen that when the parts are in folded position same are compactly related and occupy a minimum of space thereby but slightly increasing the 100

thickness of the bracelet at this point. It will further be seen that the parts can be cheaply produced by stamping and that no solder or other extraneous like fastening means is required.

For the purpose of preventing lateral movements of the end of the bracelet band which overlies or seats upon the front member 1, a stop lug or rib 20 is struck out from 10 the back member 2 and projects through the open center of the adjacent links of the bracelet band as shown in Figures 1 and 2.

It will further be observed from Figure 2 that the members 1 and 2 are nested and hence 15 occupy a minimum of space and that the end 5 of the bracelet is directly engaged with the outer face of the member 1 and seats thereon, and consequently a minimum of thickness is afforded.

20 Having thus described my invention, what I claim as new and desire to secure by Letters Patent is:—

1. In a bracelet, a front and a rear member hinged together at one end, the front member having off-set sides forming shoulders which latter are spaced and formed with spaced and opposed pairs of slots, a U-catch having side lugs at its base which extend through one pair of opposed slots and further 25 having outwardly extending finger engaging parts adjacent the free ends of the legs of the catch which project through the other pair of slots, the rear member having a pair of struck out L-shaped keepers, and the outer 30 side edges of the catch having U-cut-outs adjacent the free end of the catch to receive the keepers.

2. In a bracelet, a front and a rear member hinged together at one end, the front member having off-set sides forming shoulders which latter are spaced and formed with spaced and opposed pairs of slots, a U-catch having side lugs at its base which extend through one pair of opposed slots and further 40 having outwardly extending finger engaging parts adjacent the free ends of the legs of the catch which project through the other pair of slots, the rear member having a pair of keepers engageable with the sides 45 of the catch at the free ends of the latter.

3. In a bracelet, a pair of members hinged together at one end, one of the members having two pairs of opposed slotted parts, a U-shaped catch having a pair of lugs adjacent its base which project through the slots of one of the pairs of slotted parts, and further having a pair of fingers engaging parts on its legs which freely project through the slots of the other pair of slotted parts, and 55 L-shaped keepers carried by the other member, said catch having U-cutouts in the outer side edges of its legs to receive the keepers.

4. In a bracelet a pair of members hinged together at one end, one of the members having two pairs of opposed slotted parts, a

catch having a pair of lugs adjacent its base which project through the slots of one of the pairs of slotted parts, and further having a pair of finger engaging parts which freely project through the slots of the other pair of slotted parts, and keepers carried by the other member to engage the catch.

In testimony whereof I have signed my name to this specification.

LOUIS J. VETTER.
